UNITED STATES PATENT OFFICE.

JESSIE ALONZO SHOOK, OF BRONTE, TEXAS.

KNOCKDOWN AND PORTABLE FRAME AND HOIST.

1,257,033.

Specification of Letters Patent. Patented Feb. 19, 1918.

Application filed May 16, 1917. Serial No. 169,050.

To all whom it may concern:

Be it known that I, JESSIE A. SHOOK, a citizen of the United States, residing at Bronte, in the county of Coke, State of Texas, have invented a new and useful Knockdown and Portable Frame and Hoist; and I do hereby declare the following to be a full, clear, and exact description of the invention, such as will enable others skilled 10 in the art to which it appertains to make and use the same.

This invention relates to a hoisting apparatus for hoisting various commodities.

One of the objects of the invention is to provide a hoist including an improved combined knock down and portable frame, whereby the entire hoisting apparatus may be arranged in a comparatively small compass for easy and convenient transportation 20 from one place to another.

A further object of the invention is to provide a top beam consisting of a plurality of parallel strips or bars suitably spaced by spacing blocks, the spacing blocks at the 25 ends of the beam being so arranged as to afford sockets for the reception of the supporting legs.

In practical fields, the details of construction may necessitate alterations, falling 30 within the scope of what is claimed.

The invention comprises further features and combination of parts, as hereinafter set forth, shown in the drawings and claimed.

In the drawings:—

Figure 1 is a view in side elevation of the 35 improved hoisting apparatus constructed in accordance with the invention.

Fig. 2 is a plan view, showing the bars or strips of the beam suitably spaced by spacing blocks.

Fig. 3 is a detail perspective view of one 40 end of the beam, showing the sockets or openings for the reception of the extension of the supporting legs.

Fig. 4 is a detail perspective view of one 45 pair of supporting legs showing the extensions thereof in position ready to enter the sockets or openings of the beam.

Referring more especially to the drawings, 50 1 designates an elongated beam which comprises a plurality of parallel bars, two outer bars 2, and an intermediate bar 3, which are held spaced by the spacing blocks, or members 4 and 5 at the ends of said beam, 55 and by the central spacing block 6, there being bolts 7 passing through said bars and

blocks, and provided with nuts 8 to hold said parts firmly and rigidly together.

The spacing blocks 4 and 5, respectively, are spaced from each other, in order to form 60 the openings or sockets 9. The beam 1 is supported by two pairs of supporting legs 10 and 11. The legs of each pair are arranged to converge together upwardly, and are held so arranged by the transverse beams 65 or bars 12, 13 and 14, which are disposed transversely. Both pairs of legs are inclined toward each other, and the upper ends of said legs terminate in extensions 15, and where the extensions merge or extend from 70 the legs, shoulders 16 are formed. The transverse bars or pieces 12 to 14 so brace or reinforce the legs as to prevent them from moving longitudinally. To further prevent such movement, intersecting bars 75 or strips 17 are arranged to connect the legs. The legs of each pair are so disposed as to provide spaces 18 between the extensions 15 of the legs, whereby said extensions, when received in the sockets or openings 9, engage 80 on both sides of the intermediate bar or strip of the beam, so that the beam will rest upon the shoulders 16 and the transverse bars 14, thereby rigidly supporting the beam 1. Arranged in the spaces 19 and 20 85 between the bars 2 and 3, and mounted upon the pin 21 are pulleys 22 and 23. Arranged in the space 20 and mounted upon the pin 24, is a pulley 25. One end of a cable 26 is attached to an eye 27 of a bolt 28, which 90 is carried by one of the bars 2 of said beam 1. A windlass 29 comprising a crank shaft 30 (which is mounted in bearings of the legs 11) and a winding drum 31 (which is carried on the shaft) is provided, and to the 95 drum of which one end of a cable is attached. The cable 32 is wound partly on the drum and its other end has an eye 33. The cable 26 extends downwardly from the eye 27 and passes over the pulley 34 of the 100 block 35 (which is provided with a commodity engaging hook 36) and upwardly over the pulley 22, then downwardly and under the other pulley 37 of said block. The cable 26 after passing under the pulley 105 37 extends upwardly and over the pulley 23, then over the pulley 25, whereby its hook 38 may engage the eye 33 of the cable 32. By this construction, of hoisting apparatus, various commodities may be raised 110 by attaching them to the hook 36 and subsequently imparting revoluble movement to

the windlass. In practice, the frame may be any suitable height, preferably from thirty to forty feet whereby the commodities, when raised, may be swung into the body of a suitable vehicle, not shown. The frame may be easily and conveniently knocked down or collapsed by withdrawing the extensions 15 from the sockets or openings 9 of the beam, then arranging the legs in parallelism with the beam 1, whereby the apparatus may be transported from one place to another.

The invention having been set forth, what is claimed as new and useful is:—

- 15 1. In a device as set forth, an elongated beam, comprising a plurality of elongated bars spaced in parallelism to each other, two pairs of spacing blocks between the bars at each end, said blocks of each pair being spaced, whereby sockets are formed, supporting legs in pairs at each end, the upper ends of the legs of each pair having reduced rectangular extensions fitting in said sockets; lateral bracing means for the legs of each pair, certain of said bracing means of the legs abutting under the beam, thereby reinforcing the legs with relation to the beam and vice versa, spacing blocks centrally of the beam and between the bars thereof, said beam having spaces between the central blocks and the innermost blocks at the ends of the beam for the reception of lifting elements, and bolts passing through

the bars and the blocks to insure a rigidly constructed beam.

2. In a device as set forth, an elongated beam, comprising a plurality of elongated bars spaced in parallelism to each other and having their side faces adjacent each other, two pairs of spacing blocks between the bars at each end of the beam, said blocks of each pair being spaced and having their adjacent edges inclined in parallelism, whereby sockets are formed, supporting legs in pairs at each end of the beam, the upper ends of said legs of each pair having reduced rectangular extensions fitting inclined sockets, lateral bracing means for the legs of each pair, said legs of each pair immediately adjacent the reduced extensions having shoulders which together with certain of said bracing means of the legs abut under the beam, thereby reinforcing the legs with relation to the beam and vice versa, said spaces between the central portions of the bars of the beam adapted for the reception of lifting elements, and bolts passing through the bars and the blocks to insure a rigidly constructed beam.

In testimony whereof I have signed my name to this specification in the presence of two subscribing witnesses.

JESSIE ALONZO SHOOK.
